UNITED STATES PATENT OFFICE.

FREDERIC W. LORD AND FREDERIC WM. ERICKSON, OF NEW YORK, N. Y.

ELECTRICAL-CURRENT INTERRUPTER.

No. 852,186.

Specification of Letters Patent.

Patented April 30, 1907.

Application filed January 28, 1907. Serial No. 354,488.

To all whom it may concern:

Be it known that we, FREDERIC W. LORD and FREDERIC WM. ERICKSON, both residing at New York, in the county of New York and State of New York, have invented certain Improvements in Electrical-Current Interrupters, of which the following is a specification.

The present invention relates to means for grounding electric circuits when an abnormal current comes upon the line such as lightning discharges and surges of potential exceeding the safety limit of the established circuit.

Since the installation of power plants having transmission lines, carrying a potential of 50,000 volts or over, many difficulties have arisen as to the proper safeguarding of the wires and the appliances connected with them. It is apparent that the ordinary arresters used on low potential circuits would break down from the initial potential with any lightning discharge if employed with such high potential lines. It therefore becomes necessary to provide means for establishing an easy path for the lightning discharges separating from these discharges the dynamic current which would follow the break down of the medium caused by the lightning discharge.

The means about to be described provide for a large number of rapidly moving air gaps in the aggregate having sufficient resistance to safely prevent the normal current from discharging to the ground; and at the same time providing an opportunity for the lightning discharges or surges of abnormal potential to jump from one to the other of the various spark gap parts to the ground. All of which we will now proceed to describe and point out in the appended claims.

Of the accompanying drawings which illustrate the invention: Figure 1 is a longitudinal view partly in section of the invention, and Fig. 2 is a vertical section on line x , x , of the former figure.

In the drawings, W represents an inclosing case for the parts of the arrester, provided on each end with hubs, o and p , through which extend the shafts F , F' , from the respective motors O and P ; these are preferably electrical motors: At the outset it may be said that the construction about to be de-

scribed may not be that used in actual practice, although the features of the invention 55 are plainly indicated thereby.

The lower portion A of the inclosing case is composed of metal preferably cast in one piece, having at its underside a lug a in which is located a ground wire J , held in place by the set screws d ; the upper edge of the portion A is rabbeted at r to receive the upper portion B which is made of some suitable insulating material as glass or porcelain and is provided with a cover C , having at its central 65 portion a lug s into which is secured by the set screw e a branch I from the line wire L , W .

Secured to the lug s by the set screw f is an adjustable electrode H , consisting of a spindle t extending into the upper portion B upon the end of which is pivoted at j the depending electrode i provided on one side with the screw threaded arm h upon which is screwed the adjustable weight g , above the pivot j the electrode is forked, the two arms l , l , being adapted to strike the stop pin k in the spindle in a manner to be described. A conductor m extends from the spindle t to the electrode i to avoid the resistance of the pivoted 80 joint; while at rest the electrode i and its weight g remain in the position represented by full lines.

The shafts F and F' extend into the lower case A and meet in the common hub K , of insulating material, the former shaft is adapted to have a bearing in the hub and to rotate therein, while the latter shaft is secured in the hub by a spline or in any suitable manner and rotates with it. To the hub K is secured 85 to move therewith, the double arm electrode e , more arms may be provided if desired, the peripheries 4 and 5 of the arms are curved and serrated, and increase in diameter rearwardly and move in the direction of the unfeathered arrow.

The shaft F is attached to the hub w of the disk D through which it passes.

L , L are metal segments serrated on their inner and outer faces and separated from each other at their ends by passages 8 , 8 , these segments are secured at one end to the disk D and at their opposite ends to a ring d^2 by the bolts N , there being interposed the insulating washers M^2 on each end and the insulating 105 sleeves M . The segments L are adapted to

be rotated by means of the shaft F in the direction of the feathered arrow, contrary to the movement of the arms E.

Attached to the inner bottom of the lower portion A is a serrated metal electrode c, this electrode may be cast with the portion A if desired.

The case is to be partly filled with oil Z to immerse the lower end of the electrode i when moved to the dotted position, and not to reach the same when in the position of full lines.

On one side of the lower portion A and secured thereto is an insulated shell G having wings G² extending on each side of the disk D and ring D² this may reach over the top of the disk D if desired (with a slot for the movement of the electrode i) as indicated in the dotted lines. The office of this shell is to accentuate the force of the liquid in its centrifugal motion caused by the opposite rotation of the electrodes E and the disk D when put in motion by the respective motors and direct it toward the top of the casing, at which time the electrode i is forced forward by the oil into the dotted position against the force of the weight g and spark gap circuits are established from the electrode i to the moving segments L and from one to another, or through the arms E, to the electrode c and to ground.

When the motors are at rest and the oil is therefore quiet the weight g depresses the electrode i and causes it to move to a safe distance out from the oil so that the breaking down of the instrument is prevented by the high resistance due to the increased distance between the electrode i and any section L, this distance is determined by experiment with the maximum line voltage carried. The forks, l, as will be evident, limit the action of the weight, by their contact with the pin k, in one direction holding the electrode i in a vertical position, in the other determining the drop of the weight.

It will be seen that the oil is kept agitated by the rotation of the parts as described, and while it assists in preventing the formation of arcs, which the rapid rotation of the segments through the same aims to suppress, it also plays upon the electrode i and keeps it in a vertical position with the minimum spark gap, based on the speed of the rotating disk D, and overcomes the effect of the weight.

The construction of the peripheries of the arms E is such as to provide a compressing action on their surfaces and assist in forcing the oil through the spaces 8, 8, between the segments and over the serrated surfaces of the same.

The advantages of a series of rapidly moving serrated segments across the path of a current discharge will be apparent, as while the current is discharged to ground through

any one series of sections, another series takes its place, and arcs are dissipated rapidly, and the segments as a whole are kept comparatively cool.

I claim as my invention:

1. The combination in an arrester device of a casing partly filled with liquid insulation, inclosing and supporting spark gap electrodes, adapted to be arranged in series from the line wire to the ground, consisting of a self adjusting pivoted line electrode, a series of rotatable spark gap segments arranged in a circle, with a grounded electrode.

2. The combination in an arrester device of a casing containing liquid insulation, inclosing and supporting spark gap electrodes adapted to be arranged in series from the line wire to the ground, consisting of a self adjusting pivoted line electrode, a series of rotatable insulated spark gap segments separated from each other and arranged in a circle, with a grounded electrode.

3. The combination in an arrester device of a casing containing liquid insulation, inclosing and supporting spark gap electrodes adapted to be arranged in successive series from the line wire to the ground, consisting of a self adjusting pivoted line electrode normally free from the liquid insulation, but when the liquid is agitated changes its position and becomes immersed therein, a series of rotatable insulated spark gap segments separated from each other and arranged in a circle, with a grounded electrode.

4. The combination in an arrester device of a casing partly filled with liquid insulation, inclosing and supporting spark gap electrodes adapted to be arranged in series from the line wire to the ground, consisting of a self adjusting pivoted line electrode, a series of spark gap segments arranged in a circle and adapted to be rotated in a certain direction, a plurality of electrodes located within the said segmental circle adapted to be rotated in a direction opposite the motion thereof, with a grounded electrode.

5. The combination in an arrester device of a casing inclosing and supporting spark gap electrodes adapted to be arranged in successive series from the line wire to the ground, consisting of a self adjusting pivoted line electrode, a series of rotatable insulated spark gap segments separated from each other and arranged in a circle, with a grounded electrode.

6. The combination in an arrester device of a casing containing liquid insulation, inclosing and supporting spark gap electrodes adapted to be arranged in successive series from the line wire to the ground, consisting of a self adjusting pivoted line electrode, a series of rotatable insulated spark gap segments separated from each other by passages and arranged in a circle upon a disk or frame,

a shield at one end of the casing arranged to inclose the said segments, and a grounded electrode, as set forth.

7. The combination in an arrester device 5 of a casing containing liquid insulation, inclosing and supporting spark gap electrodes adapted to be arranged in successive series from the line wire to the ground, consisting of a self adjusting pivoted line electrode, a series of rotatable insulated spark gap segments separated from each other by passages and arranged in a circle upon a disk, a shield at one end of the casing arranged to inclose the said segments, a plurality of electrodes located within the said segmental circle adapted to be rotated in a direction opposite the motion thereof.

8. The combination in an arrester device of a plurality of electrodes separated from each other by air gaps adapted to be arranged in successive series from the line wire to the ground, consisting of a line electrode, a ground electrode, between which are a series of rotatable insulated electrodes separated from each other.

9. The combination in an arrester device of spark gap electrodes adapted to be arranged in successive series from the line wire to the ground, consisting of a line electrode and a ground electrode between which are a series of rotatable insulated electrodes separated from each other, with a plurality of electrodes located within the said series of electrodes adapted to be rotated in a direction opposite the motion thereof.

10. The combination in an arrester device of spark gap electrodes adapted to be arranged in successive series from the line wire to the ground, consisting of a line electrode normally held at a high resistance position and means for automatically forcing it into a low resistance position; and a grounded electrode; with a series of rotatable insulated electrodes between the line and ground electrode separated from each other, as set forth.

11. The combination in an arrester device of a casing containing liquid insulation, inclosing and supporting spark gap electrodes adapted to be arranged in successive series from the line wire to the ground; consisting of a self adjusting pivoted line electrode, a series of rotatable insulated spark gap segments separated from each other and arranged in a circle upon a suitable support carried by a shaft to which is attached a suitable motor, with a grounded electrode completing any series of spark gaps.

12. The combination in an arrester device of a casing containing liquid insulation, inclosing and supporting spark gap electrodes adapted to be arranged in successive series from the line wire to the ground; consisting of a self adjusting pivoted line electrode; a

series of rotatable spark gap segments separated from each other and arranged in a circle upon a suitable support carried by a shaft to which is attached a suitable motor and rotating in a certain direction, a plurality of electrodes located within the said segmental circle and carried by a shaft to which is attached a motor adapted to rotate in a direction opposite that of the first motor, with a grounded electrode completing any series of spark gaps.

13. The combination in an arrester device of a casing whose lower portion is metal and its upper portion of insulating material, provided with a cover or lid, containing liquid insulation, a line electrode supported upon the lid; a series of independent spark gap segments arranged in a circle upon a suitable support carried by a shaft which passes through the wall of the metal casing to an external motor; with a grounded electrode completing any series of spark gaps; the line electrode being automatically adjustable relative to the succeeding spark gaps, as set forth.

14. The combination in an arrester device of a casing whose lower portion is metal and its upper portion of insulating material, provided with a cover or lid, containing liquid insulation, a line electrode supported upon the lid; a series of independent insulated spark gap segments arranged in a circle upon a suitable support carried by a shaft which passes through the wall of the metal casing to an external motor, which rotates in a certain direction; a plurality of electrodes located within the said segmental circle and carried by a shaft which passes through the wall of the metal casing to an external motor rotating in a contrary direction to the first motor; with a grounded electrode completing any series of spark gaps; the line electrode being automatically adjustable relative to the succeeding spark gaps, as set forth.

15. The combination in an arrester device of a plurality of electrodes insulated from each other, adapted to be arranged in successive series from the line wire to the ground, consisting of a line electrode and a ground electrode, between which are a series of insulated electrodes separated from each other and supported by a frame which is carried by a rotatable spindle.

16. The combination in an arrester device of a plurality of electrodes insulated from each other, adapted to be arranged in successive series from the line wire to the ground consisting of a line electrode and a ground electrode, between which is a disk carrying a series of separate and insulated electrodes, adapted to be rotated by a motor.

17. The combination in an arrester device of a casing inclosing and supporting spark gap electrodes adapted to be arranged in suc-

cessive series from the line wire to the ground, consisting of an adjustable line electrode, a series of rotatable insulated spark gap electrodes separated from each other and arranged in a circle, with a grounded electrode.

In testimony whereof, we have signed our names to this specification in the presence of

two subscribing witnesses, this 18th day of January 1907.
